JULIUS VOSS, OF WIESBADEN-BIEBRICH, GERMANY, ASSIGNOR, BY MESNE ASSIGNMENTS, TO THE VISKING CORPORATION, OF CHICAGO, ILLINOIS, A CORPORATION OF VIRGINIA

PROCESS FOR PREPARING TUBULAR BODIES FROM CELLULOSE

Application filed September 5, 1928, Serial No. 304,149, and in Germany September 15, 1927.

My present invention relates to a process for preparing tubular bodies from cellulose.

The manufacture of tubular bodies from

5 cellulose has hitherto been carried out by causing cellulose solutions, especially viscose, to flow from an annular nozzle into a precipitating bath and then conducting the tubular body thus obtained in the form of a flattened band through the successive cleaning baths. The latter are generally contained in large vats provided with two superposed series of rollers which effect the transport of the band. The lower set of rollers lies 10 close to the bottom of the vat, whilst the upper set is just slightly covered by the liquid or lies close above its surface. The band passes alternately over an upper roller and a lower roller and remains almost all the time 15 in the cleaning bath.

Now this process causes considerable difficulties in the manufacture of tubular bodies, if as happens when using viscose as a starting material, in the employment of the cleaning baths, gases are formed in the interior of the tubular body, which distend it. On account of the inflation produced by the gases, the tubular body has the tendency to become 20 distended so as to form an arcuate swelling 25 where it passes over the upper roller in such manner that it is no longer in close contact with the said roller whereby the passage of the tubular body over the roller is, of course, greatly impeded. Moreover, the tubular 30 body has the tendency to burst. Therefore when working with the apparatus hitherto in use it has been necessary to discharge the gases which had collected in the body very frequently by cutting it open.

40 Now I have found that these difficulties can be overcome by not allowing the tubular body to run all the time within the cleaning baths, but causing it to travel great distances outside of the said baths, for example in such a 45 manner that the tubular body in the distance

between two successive lower rollers runs alternately 50 percent of its length inside and 50 percent of its length outside the cleaning baths.

Two preferred constructional forms of apparatus for carrying out the process according to the invention are illustrated by way of example in Figs. 1 and 2 of the accompanying drawing.

In the apparatus shown in Fig. 1 the upper series of rollers *a* is arranged at a considerable height above the surface of the cleaning bath *b*, whilst in the apparatus shown in Fig. 2 the tubular body *c* coming from the precipitating bath is first led over two or more rollers *d*, *e* and *f*, *g*, which are not arranged too close to one another, before it returns to the cleaning bath *b*. In the latter case the gases formed in the inside of the tubular body accumulate in that part *h* of the body which is between the rollers *d*, *e* and *f*, *g*, whilst in the first case they accumulate in those parts *i* of the tubular body which are situated between the upper rollers *a* and the bath. The result in both cases is that inside the tubular body considerable quantities of gas can accumulate, before their removal becomes necessary. Furthermore, the tubular body passes over the upper rollers in a flat form, so that the movement of the tubular body over the said rollers is rendered easy. In this way the device described renders it possible to manufacture tubes of more than 500 m. length without it becoming necessary to open the tube in order to let out the gases.

I have furthermore found that, by mounting the second set of rollers at a considerable height above the cleaning bath, the number and length of the vats required for the purifying operation can be diminished owing to the surprising fact that the cleaning action of the baths continues even during the time when the tubular body is outside of the bath.

I claim:

50

90

In the process for preparing a seamless tubular body from cellulose, the new step which comprises conducting the tubular body through a bath, while gas accumulates there-
5 in, in such manner that the tubular body runs alternately inside and outside of the bath, the distance the tubular body travels on the out-
10 side of the bath in each instance being at least approximately as long as the distance it travels inside the bath between its travels out-
side the bath.

In testimony whereof, I affix my signature.
JULIUS VOSS.
